J. BRUNELLI

CLOTH PRESSING AND STEAMING DEVICE

Filed Aug. 22, 1921

FIG. 2.

FIG. 3.

Inventor
James Brunelli
By his Attorneys
Edgar Hale & Co.

Patented May 1, 1923.

1,453,433

UNITED STATES PATENT OFFICE.

JAMES BRUNELLI, OF BROOKLYN, NEW YORK.

CLOTH PRESSING AND STEAMING DEVICE.

Application filed August 22, 1921. Serial No. 494,306.

To all whom it may concern:

Be it known that I, JAMES BRUNELLI, a citizen of Italy, and residing at Brooklyn, in the county of Kings and State of New York, have invented certain new and useful Improvements in Cloth Pressing and Steaming Devices, of which the following is a specification, such as will enable those skilled in the art to which it appertains to

make and use the same.

This invention relates to what are known as devices or apparatus for steaming and pressing cloth either in the piece or when made up into garments, and the object there-
15 of is to provide an improved device of this class which may be used in connection with any kind or class of cloth, but which is particularly designed for use in connection with what is known as Marvella cloth, Duvetine
20 cloth, velvet, plush and similar cloths or material having a fuzzy nap or finish; and with these and other objects in view the invention consists in a device or apparatus of the class specified, constructed and operated
25 as hereinafter described and claimed.

The invention is fully disclosed in the following specification, of which the accompanying drawing forms a part, in which the separate parts of my improvement are design-
30 ated by suitable reference characters in each of the views, and in which:—

Fig. 1 is a top plan view of my improved steam pressing device, with part of the construction broken away;

35 Fig. 2 a side view of the main framework thereof with part of the construction in section; and,

Fig. 3 a sectional view of a detail of the construction thereof.

40 In reducing my invention to practical form I provide a yoke-shaped frame *a* in which is mounted a brush roller *b* and with the open ends of the sides of which is connected as shown at *a*² a steam casing or receptacle *c* which, in the construction shown, is triangular in cross section and one of the V-shaped corners thereof is directed downwardly, and the side *c*² thereof which is directed toward the roller *b* is provided with
45 steam ports or passages *c*³ as is also the top part of the side *c*⁴ thereof opposite the side *c*².

50 The closed side of the yoke-shaped frame *a* is provided with a handle *a*³, and in connection with the frame *a* and the steam casing or receptacle *c* I provide an attachment
55

d comprising a flexible coupling *d*² which is adapted to be connected with one end of the steam casing or receptacle *c* in the usual manner as indicated at *d*³, and with which is connected a flexible steam pipe *d*⁴ having a coupling member *d*⁵ of the usual form and construction, and by means of which the pipe *d*⁴ may be connected to any suitable source of steam supply.

60 The pipe *d*⁴ is also divided centrally or at any predetermined point therein, and set into said pipe is a short coupling pipe *d*⁶ which is secured in the pipe *d*⁴ by flexible couplings *d*⁷ in the usual manner, and the pipe *d*⁶ is provided with a small tubular drain outlet *d*⁸ with which is connected or may be connected a flexible drain pipe *d*⁹ by means of which the water of condensation may be drawn off into a suitable receptacle 65 during the operation of the device or apparatus.

70 The roller *b* is composed of a central core *b*² of wood or any other suitable material and mounted thereon is a covering or enclosing wire brush like member *b*³ composed of a flexible sheet *b*⁴ in which the wire bristles
75 *b*⁵ are secured.

80 The covering or enclosing element *b*³ of the roller *b* is an article of manufacture, and is used for many purposes, and in itself it forms no part of my invention but, in practice, the inner sheet *b*⁴ thereof may be composed of rubber, leather, or a combination of canvas or other fibrous substance with
85 other material such as cardboard or the like, and the wire bristles may be secured therein in the ordinary or any desired way, and will be of sufficient rigidity to form a pressing roller. The desired result may be accomplished by a comparatively close arrangement of the wire bristles.

90 The use of my improved steam presser will be readily understood from the foregoing description when taken in connection 100 with the accompanying drawing and the following statement. In ordinary practice, the attachment *d*, or the pipe *d*⁴ thereof is connected, as hereinbefore stated, with any ordinary or preferred steam supply device 105 which will be provided with a valve in the usual manner, and the frame *a* with the roller *b* mounted therein is manipulated by the handle *a*³ in the same manner as in other devices of this class but, in this operation, the roller *b* turns on or over the material 110 which is being operated upon instead of

sliding thereon or thereover, as in the case of ordinary flat-irons, and in this operation steam is admitted into the steam casing or receptacle *c* and is discharged onto the goods which are being pressed directly in front of the roller through the perforations in the casing or receptacle *c*.

It will be understood from the foregoing description that the chief object of my invention is to properly and effectually press goods having a fuzzy or similar fibrous finish so that said finish will not be pressed down and made glossy, or deprived of its original finish, and this operation may be performed on the goods before they are made up, or in the ordinary operation of pressing garments made of such goods, but in addition to using my improved steam presser in connection with goods of the class specified, either in cloth form or when made up into garments my improved steam presser may also be used in connection with ordinary woolen cloth, either before or after it is made into garments.

It will also be understood that while I have shown and described certain details of construction for carrying my invention into effect and also have described ordinary wire for use as bristles, it will be understood that other material may be substituted for wire, and other changes in and modifications of the details of construction herein shown and described may be made, within the scope of the appended claims, without departing from the spirit of my invention or sacrificing its advantages.

Having fully described my invention, what I claim as new and desire to secure by Letters Patent, is:

1. In an apparatus of the class described, a yoke-shaped frame provided with a handle, a roller rotatably mounted in said frame, the face of which is provided with projecting and substantially rigid bristles and a perforated steam casing or receptacle mounted in connection with said frame in front of said roller.

2. In an apparatus of the class described, a yoke-shaped frame provided with a handle, a roller rotatably mounted in said frame, the face of which is provided with projecting and substantially rigid bristles, a perforated steam casing or receptacle mounted in connection with said frame in front of said roller and a flexible steam supply device connected with one end of said casing or receptacle.

3. In an apparatus of the class described, a yoke-shaped frame provided with a handle, a roller rotatably mounted in said frame, the face of which is provided with projecting and substantially rigid bristles, a perforated steam casing or receptacle mounted in connection with said frame in front of said roller, a flexible steam sup-

ply device connected with one end of said casing or receptacle and provided intermediate of the ends thereof with a drain discharge.

4. An apparatus of the class described comprising a suitable frame, a roller rotatably mounted in said frame and provided with a rigid bristle face, and means on the frame for discharging steam onto a suitable workpiece in front of said roller.

5. An apparatus of the class described comprising a suitable frame, a roller the face of which is provided with a multiplicity of closely arranged and substantially rigid projecting members, said roller being rotatably mounted in said frame, and a steam casing in said frame forwardly of said roller.

6. An apparatus of the class described, comprising a suitable frame, a roller the face of which is provided with a multiplicity of closely arranged and substantially rigid projecting members, said roller being rotatably mounted in said frame, a steam casing in said frame forwardly of said roller, and means for supplying steam to said casing.

7. An apparatus of the class described, comprising a suitable frame, a roller the face of which is provided with a multiplicity of closely arranged and substantially rigid projecting members, said roller being rotatably mounted in said frame, a steam casing in said frame forwardly of said roller, and means for supplying steam to said casing, and said frame being provided with a handle member.

8. An apparatus of the class described, comprising a suitable frame, a roller mounted therein and provided with a wire bristle face, a substantially V-shaped steam casing mounted in the frame forwardly of said roller, one corner of said casing being directed downwardly, and said casing being provided with apertures at the opposite sides thereof through which steam in said casing is adapted to pass.

9. An apparatus of the class described, comprising a suitable frame, a roller mounted therein and provided with a wire bristle face, a substantially V-shaped steam casing mounted in the frame forwardly of said roller, one corner of said casing being directed downwardly, and said casing being provided with apertures at the opposite sides thereof through which steam in said casing is adapted to pass, and means for supplying steam to said casing.

10. An apparatus of the class described, comprising a suitable frame, a roller mounted therein and provided with a wire bristle face, a substantially V-shaped steam casing mounted in the frame forwardly of said roller, one corner of said casing being directed downwardly, and said casing being provided with apertures at the opposite sides

thereof through which steam in said casing is adapted to pass, means for supplying steam to said casing, and a condensation pipe in said last named means.

- 5 11. An apparatus of the class described, comprising a suitable frame, a roller mounted therein and provided with a wire bristle face, a steam casing mounted in said frame forwardly of said roller and provided with 20 apertures, means for supplying steam to said casing, said steam being adapted to be directed downwardly onto a workpiece in front of said roller, and said frame being provided with a handle member.
- 10 12. An apparatus of the class described, comprising a suitable frame, a roller mounted therein and provided with a wire bristle 25 face, a substantially V-shaped steam casing mounted in the frame forwardly of said roller, one corner of said casing being directed downwardly and one side face of the casing being provided with apertures, means coupled with said casing for supplying steam thereto and for discharging the same through the apertures therein onto a suitable workpiece in front of said roller.

In testimony that I claim the foregoing as my invention I have signed my name in presence of the subscribing witnesses this 20th day of August, 1921.

JAMES BRUNELLI.
